UNITED STATES PATENT OFFICE.

CHARLES BIRTH, OF KINGSTON BOROUGH, PENNSYLVANIA, ASSIGNOR TO WALES ADDING MACHINE COMPANY, OF WILKES-BARRE, PENNSYLVANIA, A CORPORATION OF PENNSYLVANIA.

CALCULATING-MACHINE.

1,318,641.

Specification of Letters Patent.

Patented Oct. 14, 1919.

Application filed July 31, 1918. Serial No. 247,576.

To all whom it may concern:

Be it known that I, CHARLES BIRTH, a citizen of the United States, residing in the borough of Kingston, Luzerne county, Pennsylvania, have invented new and useful Improvements in Calculating-Machines, of which the following is a specification.

This invention is particularly directed to that type of transfer or carrying mechanisms for calculating machines, comprising carrying members operable independently of the usual adding racks or drive members, and normally held in set or cocked position by counter-controlled, spring-pressed detents, which, when tripped, release the carrying members to the action of drive springs. The drive springs actuate the members in one direction to effect the transfer. Carry-resetting means restores the discharged carrying members to normal position, whereupon, the detents again become effective to lock the carrying members in set or cocked position.

The carrying members shift in their carrying and resetting operations, relatively to their detents, which are displaced by cams on the counters as the latter turn from their "9" to their "0" positions (in the decimal system), the detents being journaled, or pivotally supported to swing into and out of effective position.

It is apparent that, should a detent fail to become effective because of sticking in displaced position, or for any other reason, the corresponding carrying member would not be locked in reset position, and upon the withdrawal of the resetting means the carrying member would immediately advance to add an undesired "1" to its corresponding counter and render the computation inaccurate.

One object of this invention is to insure the positive return of the detent to locking position relatively to its carrying member as the latter is reset.

This, I effect by contriving to limit the displacement of which the detent is capable, and arranging self-contained means to forcibly overcome any opposition to its return to locking position.

As a result, I have improved the operation of the machine and materially reduced the liability of improper accumulation.

To these ends, the invention includes certain novel features and combinations of parts, all of which will be more fully set forth hereinafter and particularly pointed out in the claims.

In the accompanying drawings—

Figure 1 is a sectional view of the well known Wales calculating machine, equipped with one embodiment of my invention, parts being omitted and broken away;

Fig. 2 is a fragmentary plan view;

Fig. 3 is a detail side view of the accumulating mechanism showing the counters in normal idle position, the machine being at rest;

Fig. 4 is a similar view, showing the positions assumed by the parts at the end of the forward stroke of the main drive shaft;

Fig. 5 is a detail side view of the transfer mechanism at a period near the end of the return stroke, but prior to the disengagement of the counters and their drive members, showing the carrying detent tripped, and its carrying member partially advanced to prevent restoration of the detent to effective position;

Fig. 6 is a similar view, showing the carry completed; and

Fig. 7 is a detail perspective view of one of the detents for the carrying members.

A base 968 (Fig. 1) supports side frames 969^a, one only of which is shown in Fig. 2, between which are mounted the keyboard or indexing section, and the counter or accumulating section, with its operating connections.

The numeral keys 117 of the keyboard are arranged in denominational rows, the respective keys in each row adapted to individually control by means of levers 116, the separate stops 115, arranged in corresponding denominational files.

Depression of any of the keys 117 shifts the corresponding stops into the paths of denominational positioning bars 310, there being a positioning bar for each file of stops.

Front arms 312 journaled on a cross shaft 100

300, and rear arms 311 journaled on a cross rod 301, support the individual positioning bars 310, to enable the latter to advance and retire relatively to the stops 115.

5 Restoring links 312 depending from offsets 312^m of the front supporting arms 312, are forked at their lower ends to embrace and rest upon a restraining and restoring bar 294 mounted in rocking levers 220 10 journaled on a cross rod 508^a. The cross rod 508^a is conveniently mounted in posts 968^m extending upwardly from the base 968.

The restraining and restoring bar 294 normally lies at one end of its stroke to retain 15 the positioning bars and connected parts in retired position against the influence of springs 383 which connect the restoring links 312^a with a slotted guide plate 220^b fastened to the restraining and restoring bar 294. The forked ends of the links enter the 20 slots in the plate 220^b for guidance, the plate also operating to prevent lateral displacement of the links.

Rolls 340^a carried on swinging arms 323 25 journaled on the cross shaft 300 extending between the side frames, or on a tube 300^b surrounding the shaft, enter cam slots 220^m formed in the rocking levers 220 to operate the latter.

30 A trip rod 303 connects the swinging arms 323, to form therewith an oscillatory frame swung by links 214 which connect the frame with cranks 212 on the main drive shaft 200.

A main restoring spring 285 connected to 35 the main drive shaft 200, returns the shaft and connected parts to, and holds them in, their normal positions of rest.

Turning the main drive shaft forwardly 40 against the tension of the restoring spring 285 swings the arms 323 forwardly to cause their rolls 340^a to traverse the cam slots 220^m in the levers 220, and rock the latter downwardly. The levers 220, in turn, withdraw the restraining and restoring bar 294 45 from the lower ends of the restoring links 312^a and further tension the springs 383 to cause the links 312^a to follow the bar 294 and swing the front supporting arms 312 forwardly to advance the positioning bars 50 310.

The positioning bars advance until arrested either by one or another of the key-set stops 115 previously projected into the paths of the positioning bars by the depression of the numeral keys 117, or by rack detents 221 journaled on a cross rod 202 mounted in the side frames 969^a. The key-set stops 115, when projected, displace the rack detents 221 from the paths of the positioning bars.

A series of denominational, arcuate, toothed adding racks or drive members 410, whose stocks 410^m are journaled on a cross rod 401 mounted in the side frames, are con-

nected at 450 to their respective denominational positioning bars 310 and partake of their travel.

An axle 400 mounted in arms 414 journaled on a cross rod 404 and extending over the drive members 410, supports for independent rotation, a series of denominational counters 490^x, located adjacent their respective denominational drive members 410.

Two sets of counters 490 and 490^x, and their coacting mechanisms, are shown, and 75 are substantial duplicates. Hence, a description of one will suffice for both.

Pinions 435 (Figs. 2-6) fastened to the respective counters 490^x, are adapted to mesh with and be turned by the toothed racks or 80 drive members 410.

The pinions 435 are interposed between the series of drive members 410 and a series of combined carrying and counter locking bars or members 610 slidably supported for 85 endwise travel on parallel front and rear cross rods 600, and provided with teeth 610^p (Figs. 3-6) with which the pinions 435 normally mesh. Detents 612 journaled on the rear cross rod 600 engage the respective carrying and locking bars 610 to normally hold 90 them against shifting.

When the drive shaft 200 is in its position of rest, at the end of its return stroke, the pinions 435 are engaged with the carrying members 610 and disengaged from their drive members 410 (Fig. 3). Counter-supporting means, including vertically shiftable plates 324 (Fig. 2) located at opposite sides of the machine, and on which the opposite ends of axle 400 rest, maintain the pinions 435 in engagement with their combined carrying and locking members 610.

The means for shifting the supporting plates 324 is not especially pertinent to the 105 present invention, and is omitted from this specification, a full description thereof being contained in the copending application of Pentecost *et al.*, filed July 17, 1918, Serial No. 245,273.

Suffice it to say that in adding operations, the counter pinions 490^x are maintained in engagement with their control members 610 and held disengaged from their control members 410 during the forward stroke of 115 the main drive shaft 200, whereby to enable the positioning bars 310 and racks or control members 410 to advance freely until arrested by the key-set stops 115, or the rack detents 221, as above explained.

As the main drive shaft approaches the end of its forward stroke, it trips the counter-supporting mechanism (not shown) to effect the disengagement of the counter pinions 435 from their locking members 610 125 and the engagement of the pinions with the drive members 410 (Fig. 4).

At the end of the forward stroke, the

main drive shaft is released to the action of the restoring spring 285 which returns the shaft to its home position.

The main drive shaft, on its return stroke, 5 forces the swinging arms 323 rearwardly, to cause the rolls 340^d to retrace their paths along the cam slots 220^m, thereby rocking levers 220 and the restraining and restoring bar 294 upwardly to their home positions.

10 The restraining and restoring bar presses the restoring links 312^d upwardly to retire the arms 312, 311 and the positioning bars 310 and racks 410.

The advanced racks or drive members 15 410, as they retire, turn the counters 490^x to register thereon an amount corresponding to that represented by the key-set stops 115.

As the main drive shaft 200 approaches the 20 end of its return stroke, and immediately subsequent to the complete retirement of the drive members, it restores the displaced counter-supporting mechanism (not shown) to disconnect the pinions 435 and counters 25 490^x from their drive members 410 and re-engage the pinions with their toothed carrying and locking members 610. The pinions are maintained in such position until, in adding operations, the main drive shaft 30 again approaches the end of its forward stroke.

As the capacity of a counter of lower denomination is exceeded, the excess digit is transferred to the counter of next higher 35 denomination, and in machines of the type herein shown, such transfers must be initiated while the counters are engaged with their drive members, although the actual transfer does not occur until the counters 40 are disengaged from their drive members 410 and engaged with their combined carrying and locking members 610.

The transfer mechanism (Figs. 2-6) embodies several independently operable groups 45 of carrying devices, each of which includes a combined carrying and locking member 610, driven by a spring 680; a detent 612 to releasably retain the carrying member in set or cocked position; and a cam or trip member 411 controlled by the counter of 50 lower denomination, to displace the detent, when the capacity of the lower counter is exceeded.

In addition, a carry-resetting bar 613 is 55 provided, which not only restores the discharged carrying members 610 to set or cocked position, but also controls their discharge.

The action of the respective groups of 60 devices forming the transferring mechanism may continue successively across the machine from right to left in a carrying "wave", after the disengagement of the counters and drive members is completed,

and until the counters are disengaged from 65 the combined carrying and locking members 610 at the end of the succeeding forward stroke of the main drive shaft.

This is effected because each carrying group may control the group of next higher 70 order, depending upon the amount registered on the counters.

Since the counters 490^x, in their rotation, 75 control the transferring mechanism, it is obvious that such mechanism must be arranged to respond at varying times or periods in the operation of the machine, as determined by the amount already registered on the counters and the amount which is being added thereto in any one operation 80 of the machine.

The detents 612 journaled on the rear cross rod 600 adjacent the respective carrying members 610, have lugs 612^m extending over and resting upon the bottom edges of 85 slots 610^r formed in the carrying members, the lugs lying in the paths of shoulders 612^p in the bottom edges of the slots of the carrying members, to retain the members in cocked or set position against the tension 90 of the springs 680 attached to the front ends of the bars 610, and to an anchor plate 923 extending between the side frames. Lateral ears 612^e on the several detents extend oppositely to the lugs 612^m, into the paths of 95 cams 411 fixed to turn with the respective counters 490^x. Springs 681 maintain the detents effective.

Detents 612^a, similar to detents 612, are journaled on the front cross rod 600 to co- 100 operate with the carrying bars 610^a of the front series of counters 490, in like manner.

Fig. 3 shows the front and rear sets of 105 counters 490, 490^x engaged with their respective combined carrying and counter-locking members 610, 610^a which is the position of rest of the parts prior to the forward stroke.

The full line positions of the tripping cams 411 indicate that both sets of counters 110 are cleared or registering zeros.

The dotted line position of the cam 411 of the rear set of counters 490^x, indicates the position assumed when the counter registers "9".

Fig. 4 shows the positions of the parts at 115 the end of the forward stroke, during an adding operation, the rack 410 having advanced until arrested by the key-set stop 115, in position to accumulate "9" on the 120 rear counter 490^x, which has just dropped into mesh with its rack, such counter being clear.

Assuming that the counters 490^x already 125 register 39 and 29 is to be added thereto, the proper keys 117 are depressed and the main drive shaft turned forwardly. The two positioning bars 310 of lowest denomina-

nation advance on the forward stroke of the main drive shaft, independently of the counters, until arrested by contact with the key-set stops representing the number 29.

5 The positioning bars corresponding with the remaining counters of higher denomination advance until arrested by the usual detents 221. The active positioning bars, on their advance, draw with them the drive members 410, the positioning bar and drive member 410 associated with the counter of lowest denomination advancing much farther to represent "9" than does the positioning bar and drive member of next higher order which advances only sufficiently to represent "2".

After the counters 490^x engage the advanced drive members, and during the return stroke of the main drive shaft, the advanced drive members are retired, during which retirement the two drive members of lowest denomination turn the counters to add the amount "29" to the amount already registered.

25 The drive member which has advanced the farthest to represent the higher digit is the first to begin its retirement; in this example, the drive member of lowest denomination. Thus, the counter of lowest 30 denomination will commence to turn before the counter of next higher denomination.

Obviously, since its counter already registers "9", the drive member will only have to move one step in such retirement, to turn 35 the counter to "0".

The counter 490^x of lowest denomination as it turns from its "9" to its "0" position, wipes its cam 411 against the corresponding ear 612^r of the detent 612 which locks the carrying member 610 associated with the counter of next higher denomination, to swing the detent upwardly against the tension of its retaining spring 681, thereby displacing the lug 612^m from in front of the shoulder 612^p on said carrying member to free the carrying bar which coöperates with the counter pinion 435 of next higher order, to the action of its spring 680.

Obviously, if the carrying member 610 50 was permitted to complete its operation at this time (while the pinion is engaged with its drive member 410 and disengaged from the carrying bar and detent 610) such operation would be futile, that is to say, it 55 would advance without turning the counter, and the carry would be lost. On the other hand, if the carrying bar, when tripped, was held against any advance, the cam 411, which passes out of contact with the lug 612^r 60 as the counter reaches its "0" position, would allow the detent 612 to snap back into its former effective position, and again lock the carrying bar against operation. Therefore, the carrying bar 610 is permitted a

slight displacement, when tripped, relatively 65 to its detent 612, sufficiently to locate its shoulder 612^p beneath the lug 612^m of the detent (see the left hand carry, Fig. 5) to prevent the detent from resuming its effective position, after which the released carrying bar 610 is arrested before it has completed its effective throw. The arresting means also operates to release the bar for complete operation subsequently to the disengagement of the counters 490^x and their 70 drive members 410, and their engagement with the carrying bars, and to restore the bar to normal set position in readiness to perform another carrying operation subsequently to the engagement of the counters 75 80 with their drive members near the end of the succeeding forward stroke, and their consequent disengagement from the carrying bars.

In following the sequence of operations 85 of the machine, it will be necessary to first explain the method of resetting the carry, which operation occurs prior to the carry-delaying operation, before explaining the carrying operation.

90 Arms 611^a (Figs. 1, 3 and 4) journaled on the cross shaft 401 near its opposite ends, support a cross rail 690 on which is mounted a carry-delaying and resetting bar 613, one edge of which projects rearwardly beyond 95 the rail 690, in front of the forward ends of the carrying bars 610 and 610^a, and is preferably flanged to afford a wide contact face to coöperate with the forward ends of the carrying bars.

100 Normally, the arms 611^a rest against projecting studs 652^a mounted in the free arms of bell cranks 611^f pivoted to the respective side frames at 652, to support the carry-delaying and resetting bar 613 in its retracted position, shown in full lines in Fig. 3, at which time it is farthest removed from the carrying bars 610 and 610^a.

105 The levers 220, heretofore referred to, which control the advance and retirement 110 of the drive members 410, and rock downwardly and then upwardly during the operation of the machine, carry pins 250 (Figs. 3 and 4) entered in slots 611^m formed in the lower ends of links 611^b connected to 115 the remaining arms of the bell cranks 611^f.

120 During the major portion of the forward stroke, the pins 250 idly traverse the slots 611^m to afford time for the advance of the drive members 410, and the disengagement 125 of the pinions 435 from the carrying members 610 and their engagement with the drive members. Just prior to the end of the forward stroke, and immediately subsequent to the engagement of the counters 490^x or 490 with their drive racks 410, and their consequent disengagement from the carrying bars 610 or 610^a, the pins 250 contact

the lower end walls of the slots 611^m to draw the links 611^b downwardly and rock the bell cranks 611^f, the free arms of which, carrying the studs 652^a, force the latter against 5 the arms 611^d to swing the delaying and resetting bar 613 rearwardly to the opposite end of its travel and tension the resetting bar restoring springs 685^d. This position is shown in Fig. 4. The bar 613, 10 during such operation, strikes the forward ends of such of the carrying bars 610 or 610^a as have been discharged during the previous operation of the machine, to restore the carrying bars against the tension 15 of the carrying springs 680, while the counters are disengaged therefrom.

The resetting bar 613 presses the carrying members 610, 610^a rearwardly past their normal locked positions to insure that the 20 shoulders 612^p shall retreat past the lugs 612^m on the detents 612, to permit springs 681 to snap the detents back to effective position with their lugs 612^m in front of the shoulders 612^p. Hence, during its final 25 travel, the resetting bar contacts the forward ends of all of said carrying members of one set or the other, even those which are in cocked position, to force them back slightly. At the end of the forward stroke, 30 all the carrying springs 680 of one set of carrying members 610, as well as the resetting bar restoring springs 685^d, tend to return the resetting bar to normal position.

The counters 490 or 490^x at this point in 35 the operation of the machine are now controlled by drive racks 410, and at the beginning of the return stroke the pins 250 withdraw from the lower ends of the slots 611^m, to enable the restoring springs 685^d, 40 aided by the tensioned carrying springs 680, to return the resetting bar 613 toward its normal retracted position.

The carry-resetting bar 613 is arrested intermediate the ends of its return stroke, in 45 position to delay the carrying members 610 in tripped position, as follows:

The trip rod 303 (Fig. 3) normally lies in front of and in contact with projections 611^p carried by locking members 611^e, 50 slotted to accommodate and travel back and forth transversely of their supporting studs 963^a and 963^c extending inwardly from the opposite side frames 969^d. The trip rod thus restrains the locking members 611^e against 55 the action of springs 685.

The forward ends of the locking members 611^e are each formed with stepped shoulders 661^r, 611^s, and 611^t, and, as the trip rod 303 advances during the forward stroke, the 60 springs 685 project the locking members 611^e until, at the end of the forward stroke, the lower innermost shoulders 611^r strike lugs 611^v on the links 611^b, (see Fig. 4), which lugs have entered the paths of the

shoulders 611^r as the links were drawn 65 downwardly by the studs 250 and levers 220. At the end of the forward stroke, the lugs 611^v lie below and apart from the overhanging shoulders 611^s.

The withdrawal of the studs 250 from 70 the lower ends of the slots 611^m of the links 611^b, frees the links and the resetting bar 613 to the action of the tensioned restoring springs 685^d aided by the carrying springs 680, which rock the resetting bar forwardly 75 toward its idle position, and the latter rocks the bell crank levers 611^f to lift the links 611^b.

The overhanging shoulders 611^s, however, still lie in the paths of return of the 80 lugs 611^v to arrest the links 611^b and the carry-resetting bar before the latter has completed its return to idle position, as shown in dotted lines in Fig. 3.

This partial restoration of the links 611^b 85 and carry-resetting bar 613 occurs just prior to the actuation of the drive members 410 by the restraining and restoring bar 294 on its return (Fig. 1), and is sufficient to shift the resetting bar 613 from its active re-setting position, shown in Fig. 4 to the intermediate position, shown in dotted lines in Fig. 3, and in full lines in Fig. 5, wherein it permits the slight advance of 90 such of the carrying bars 610 as may thereafter be released by the tripping cams 411 and detents 612 during the retirement of 95 the drive members 410 to normal position.

Fig. 5 shows the position to which the rack 410 has turned a counter of lower denomination after having added "1" to such counter, which previously registered "9". The counter, in rotating from its "9" to its "0" position, has caused its cam 411 to trip the detent 612 pertaining to the carrying 100 bar 610 associated with the counter of next higher denomination, to release the carrying member 610, which has advanced through its preliminary travel until arrested by the carry-delaying bar 613, which occupies its 105 intermediate position.

Such slight advance of the tripped carrying member 610 takes place immediately upon the displacement of the detent 612, and is sufficient to bring the shoulder 612^p of the 110 member 613 under the lug 612^m of the displaced detent to prevent the return of the latter, after the cam 411 wipes past the detent.

The locking members 611^e maintain the 115 carry-delaying and resetting bar 613 in its intermediate position during the retirement of the drive members 410, which latter arrive at their home positions, prior to the completion of the return stroke of the main 120 drive shaft 200, further movement of which then has no effect on the members 410, owing to the shape of the rear ends of the cam 125

slots 220^m. The counters are disengaged from their drive members and engaged with the racks 610^p, on the carrying members 610, during the final return travel of the main 5 drive shaft, after which the trip rod 303, as it completes its return stroke, contacts the projections 611^p to restore the locking members 611^e to normal position, shown in full lines in Fig. 3, thereby freeing the links 10 611^b to enable the restoring springs 685^d to return the resetting bar to normal retracted position and in so doing lift the links until the lugs 611^v thereon strike the overhanging shoulders 611^t to arrest the resetting bar 15 in retracted position.

Such of the carrying members 610 as have been tripped by the numeral wheel cams 411, of lower order, will follow the resetting bar on its withdrawal, due to the tension of carrying springs 680, as shown in Fig. 6, 20 thereby turning their respective counters of higher order one step to effect the carry, the bars 610 being prevented from turning the counters farther, by contact of the rear ends 25 of their slots 610^m with the front cross rod 600, which serves as an overrotation preventer for the carrying mechanism.

Fig. 6 shows the position of the tripping cam 411 on the counter 490^x of higher order, 30 after the carrying member 610 has added "1" to the counter, which previously stood at zero, the parts being shown in their positions at the end of the return stroke.

The tripped carrying bars remain in dis- 35 charged position until restored by the resetting bar 613 near the end of the succeeding forward stroke, as heretofore explained. It will be observed, therefore, that cross carrying operations can be initiated at the end of 40 a return stroke and continue until near the end of the next forward stroke, thus permitting ample time for the completion of the operation when the machine is stroked at high speeds.

45 Thus, assume that the amount already registered on the counters is 999939 and it is desired to add 69 thereto.

The operation of the machine will be exactly as heretofore explained with reference 50 to the first example given, until after the transfer of "1" from the counter of lowest denomination to the counter of next higher denomination, at which time, it will be remembered, the main drive shaft has practically returned to its home position in the usual operation of the machine.

The drive member 410 of lowest denomina- 55 tion positively turns its corresponding counter 490^x to cause its trip member 411 to 60 positively displace the detent 612 and release the carrying member 610 associated with the counter of next higher denomination, for operation, after which, in the particular example given, the transmission of

power from the drive members 410 to the 65 carrying detents 612 ceases. Thereafter, the counters 490^x of two lowest denominations are turned by their drive members 410 to complete the addition thereto of the amount 69. 70

Upon the disengagement of the counters 490^x from their drive members 410, and their engagement with the carrying members 610, the tripped carrying member 610 operates as above set forth, under the influence of 75 its tensioned drive spring 680, to turn the counter of the second denomination one step.

But such rotation of the counter of the second denomination turns the latter from "9" to "0" and, in the example given, immediately starts a continued or cross-carrying operation. 80

At this period, owing to the complete retraction of the carry-resetting bar 613, the carrying members 610 are free to advance 85 throughout their full travel under the tension of their drive springs 680, and hence, as the counter 490^x in the second denomination rotates from its "9" to its "0" position, its tripping cam or member 411 in turn dis- 90 places the detent 612 controlling the carrying member 610 coacting with the counter 490^x of the third denomination, to free such carrying member and effect the transfer of the excess "1" from the counter of the sec- 95 ond denomination to the counter of the third denomination by the rotation of the latter counter.

As, in the example given, the counter of the third denomination already registers its 100 capacity, its rotation will turn it one step to register "0" and its tripping cam 411 will displace the detent 612 associated with the carrying member 610 appropriated to the counter 490^x of next higher or fourth de- 105 nomination, and a further transferring operation is effected.

This successive or cross carrying operation will continue across the machine on 110 counters of successively higher denominations until it reaches a counter which does not register its capacity prior to the transfer thereto of "1" from the counter of next lower denomination.

From the foregoing example, it will be 115 noted that in cross carrying, the adding racks or drive members 410 have exerted no influence whatever on any of the groups of carrying mechanisms after the first, or that associated with the counter of the second 120 denomination.

Therefore, cross carrying presents a different condition than where the carrying de- 125 tents 612, 612^a are positively and forcibly tripped by the drive members. It is necessary to depend upon the strength of the drive springs 680 of the carrying members 610 of lower order to not only turn the re-

spective counters of next higher order in transferring operations, but also to wipe the tripping cams or members of such counters of next higher order against the detents 5 612, 612^a of the carrying members 411 of successively higher order, to displace such detents against the tensions of their restoring springs 681 and of their carrying member drive springs 680, which latter press 10 the shoulders 612^p firmly against the lugs 612^m of the detents.

Furthermore, in transferring operations directly effected through the drive members, the tripped carrying members are detained 15 in their partially operated position until the counters engage the carrying members, whereas, in cross carrying operations the carrying members operate instantaneously as soon as their detents are tripped.

20 For a more complete understanding of the foregoing construction, attention is directed to U. S. patents to Wales 797,032, August 15, 1903; and to McFarland and Wales 880,157, February 25, 1908; and more particularly 25 to the copending application of Pentecost *et al.* above referred to.

It is apparent that each element of a 30 group of carrying mechanisms is important and none more so than the detents 612, 612^a which lock the carrying members 610, 610^a in set positions. If such detents should not 35 become effective, the carrying members would operate inopportunely to transfer "ones" and render the accumulation inaccurate.

The parts composing each group of carrying mechanism are reduced to the smallest size compatible with efficiency both in manufacture and operation, to render the transferring mechanism as a whole, more compact, and also to restrict the operating 40 movements of the parts to a small compass.

To absolutely insure the restoration of the 45 detents to effective position at the proper time, I have contrived a means which will accomplish this result without increasing the number of elements composing the carrying mechanism.

In other words, such positive detent- 50 restoring means is self-contained within the carrying group.

To these ends, I provide each combined carrying and counter-locking member 610 with a closed cam slot 610^c of irregular 55 shape, as illustrated in Figs. 3-6, entered by the lug 612^m of the corresponding detent 612.

The shoulder 612^p, with which the detent 612 coacts, is formed by cutting away or reducing the bottom edge of the slot 610^c intermediate its ends. The upper edge of the slot is inclined, as at 610^s, to a point 610^v in advance of the shoulder 612^p and substantially in the same horizontal plane therewith, the upper cammed edge of the slot ter-

minating at its forward end in the cutaway 65 or reduced clearance extension 610^t, in front of the shoulder 612^p.

The rear vertical face of the lug 612^m of the detent abuts the squared shoulder 612^p, the front end of the lug being beveled, as 70 at 612^s (Fig. 7) to insure its escape past the point 610^v where the cam 610^s merges into the clearance extension 610^t.

In Fig. 3, the detent 612 is shown in contact with the shoulder 612^p to retain the carrying member 610 in cocked or set position 75 against the tension of its drive spring 680.

As the trip member or cam 411 moves in a clockwise direction from its dotted line position (shown at the left in Fig. 3) to 80 its full line position, while the pinion 435 is in mesh with its drive member 410, it wipes against the ear 612^r of the detent 612 which holds the carrying member 610 of the counter of next higher denomination, in 85 cocked position. This action rocks the detent upwardly against the tension of its restoring spring 681 until the lug 612^m escapes the shoulder 612^p of the carrying member 610, whereupon the latter advances, 90 under the influence of its drive spring 680, until arrested by the carry-resetting and delaying bar 613, as above explained. The lug 612^m, however, is confined within the closed slot 610^c to limit the displacement of 95 the detent, and the shoulder 610^p then lies beneath the lug, as shown at the left in Fig. 5.

After the disengagement of the pinions 435 from their drive members 410 and their 100 engagement with the combined counter-locking and carrying members 610, the carry-resetting bar 613 is withdrawn to free the tripped carrying members 610, which thereupon advance to complete the transfer, 105 and at that time occupy the positions shown at the left in Fig. 6. The carrying bars 610 have thus shifted forwardly relatively to the lugs 612^m of the detents which now lie near the rear ends of the slots 610^c, as shown. 110

The discharged carrying bars 610 maintain this position relatively to their detents 612 until the main drive shaft approaches the end of its succeeding forward stroke, whereupon, after the counter pinions 435 have disengaged the carrying member 610 and engaged their drive members 410, the carry-resetting bar 613 is actuated, as hereinbefore explained, to reset the discharged carrying and counter-locking members 610, in which 115 operation, the carrying members are returned to a point slightly behind their normal cocked positions to insure the clearance between the shoulders 612^p and the lugs 612^m, as shown in Fig. 4. 120

It is during this operation that my invention performs its most important function.

As the carrying members are restored, the

inclined or cam edges 610^s of the slots 610^r wipe along the lugs 612^m of such of the detents 612 as may stick in elevated position, to press the detents down, the lugs following 5 the contour of the cam edges and being positively led thereby to a point in front of the shoulders 612^p on the carrying members 610.

When the carrying members 610 are fully retracted (as shown at the left in Fig. 4) 10 the cammed edges of the closed slots 610^r have forced the lugs 612^m down to the level of the extensions 610^t which then fit over the lugs to maintain them in line with, and insure the contact of the shoulders 612^p therewith when the carry-resetting member 15 is withdrawn to its intermediate position.

The bevel or chamfered portion 612^s of the lug 612^m on the detent, enables the lug to clear the point 610^v at the juncture of 20 the cam 610^s and the extension 610^t of the slot.

This beveled portion also prevents the lug 612^m from engaging the point 610^v in such manner as to prevent the displacement of 25 the detent when tripped by the cam member 411.

From the foregoing, it will be noted that a cycle of operation of the machine comprises the forward and return strokes of the 30 main drive shaft, and that whereas the carrying members 610, 610^a may be tripped at varying periods during the return and succeeding forward strokes of the main drive shaft, depending upon the amount already 35 registered on any one of the counters and the amount being registered thereon, the carry-resetting member always operates at a certain, predetermined and constant time in the forward stroke of the main drive 40 shaft to reset the carrying members, and hence I have taken advantage of this established operation to positively effect the restoration of the detents to effective position at such constant predetermined time notwithstanding the varying periods at which 45 the detents may be tripped.

Changes may be made in the form and arrangement of the several parts described without departing from the spirit and scope 50 of this invention.

What I claim as new, is:—

1. In a calculating machine, the combination with a series of denominational counters, and drive members therefor; of a transfer mechanism for the counters comprising several carrying groups, each group including a carrying member, a releasable detent supported independently of the carrying member, to lock the member in set position, 55 a spring to hold the detent effective, and a trip member to displace the detent; and means to reset the carrying member; each group also including self-contained means supplementary to the spring, to positively 60

enforce the restoration of the detent to effective position, in case of failure of the spring. 65

2. In a transferring mechanism for calculating machines, the combination with a carrying member shiftable to effect a carry; resetting means to cock the carrying member; a detent supported independently of the carrying member, to lock the carrying member in cocked position; a counter controlled by the carrying member; counter-controlled means to trip the detent; a spring 70 to return the detent to, and yieldingly hold it in, effective position; and means supplemental to the spring, to positively enforce the complete restoration of the detent to locking position, in case of failure of the 75 spring.

3. In a calculating machine, the combination with a series of denominational counters, and drive members therefor; of a transfer mechanism, including a carrying member 80 to effect the transfer; means to reset the carrying member; a detent controlled by a counter of lower denomination, to lock the carrying member in reset position, and relatively to which the carrying member shifts 85 when effecting a transfer, and when reset a spring to yieldingly retain the detent effective; said carrying member being equipped with self-contained means to positively enforce the restoration of the detent to effective 90 position independently of the spring. 95

4. In a transferring mechanism, the combination with a pair of denominational counters; and a drive member for the counter of lower denomination; of a carrying member shiftable in one direction relatively to the counter of higher denomination to turn the latter; means to reset the carrying member to cocked position; a detent supported on a stationary pivot and having its free end resting on the carrying member, to engage a shoulder thereon and lock the member in cocked position; a spring to yieldingly maintain the detent effective; and a counter-controlled trip to displace the detent; the carrying member provided with means to confine the detent against unnecessary displacement and to guide it back to effective position as the carrying member is reset, independently of the spring. 110

5. In a calculating machine, the combination with a plurality of denominational counters, and drive members therefor; of transfer mechanism, including a normally cocked carrying member; means to actuate 115 the carrying member to effect the transfer from a counter of lower denomination to one of next higher denomination; a detent mounted on a stationary pivot, to maintain the carrying member in cocked position, and adapted to be displaced by the counter of lower denomination; a spring to yieldingly retain the detent effective, the carrying 120

115

120

125

member adapted to shift relatively to the 65
detent; and a carry-resetting element to re-
store the carrying member to cocked posi-
tion, said carrying member having means

5 supplemental to and operable independently
of the spring to positively enforce the com-
plete restoration of the detent to effective
position as the carrying member is reset.

6. In a calculating machine, the combina-
10 tion with a plurality of denominational
counters, and drive members therefor; of
transfer mechanism, including a normally
cocked carrying member; means to actuate
15 the carrying member to effect the transfer
from a counter of lower denomination to
one of next higher denomination; a detent
to maintain the carrying member in cocked
20 position, and adapted to be displaced by the
counter of lower denomination; a carry-
resetting element to restore the carrying
member to cocked position; and a cam slot
25 on the carrying member to positively en-
force the restoration of the detent to effec-
tive position as the carrying member is
reset.

7. In a calculating machine, the combina-
30 tion with a plurality of denominational
counters, and drive members therefor; of
transfer mechanism, including a normally
cocked carrying member; means to actuate
35 the carrying member to effect the transfer
from a counter of lower denomination to
one of next higher denomination; a detent
to maintain the carrying member in cocked
40 position, and adapted to be displaced by the
counter of lower denomination; and a carry-
resetting element to restore the carrying
member having a closed cam slot adapted to
45 limit the displacement of the detent, as well
as to positively enforce the restoration of
the detent to effective position as the carry-
ing member is reset.

8. In a calculating machine, the combina-
45 tion with a plurality of denominational
counters, and drive members therefor; of
transfer mechanism, including a carrying
member; means to actuate the carrying
50 member in one direction to effect a transfer
from a counter of lower denomination to
the counter of next higher denomination; a
carry-resetting element to shift the carrying
55 member to set or cocked position; said carry-
ing member having a closed slot formed
therin, one wall of which is pro-
vided with a shoulder; a detent having a lug
entered in the slot and adapted to contact
55 the shoulder to retain the carrying member
in set position; means on the counter of
lower denomination to displace the detent
and release the carrying member for opera-
tion relatively to the detent; the opposite
60 wall of the slot having a cam edge leading
to a point in advance of the shoulder,

whereby to limit the displacement of the
detent, and to positively guide and enforce
its restoration to effective position as the
carrying member is reset.

9. In a calculating machine, the combina-
70 tion with a plurality of denominational
counters, and drive members therefor; of
transfer mechanism, including a carrying
member; means to actuate the carrying
member in one direction to effect a transfer
75 from a counter of lower denomination to
the counter of next higher denomination; a
carry-resetting element to shift the carrying
member to set or cocked position, said carry-
ing member having a closed slot formed
80 therein, one wall of which is cut away to
form a shoulder, a detent having a lug en-
tered in the slot and adapted to contact the
shoulder, to retain the carrying member in
set position; counter-controlled means to
85 displace the detent and release the carrying
member for operation; another wall of the
slot having a cam edge leading to an ex-
tension slot in advance of the shoulder to
positively guide and enforce the restoration
90 of the detent to effective position.

10. In a calculating machine, the combina-
95 tion with a pair of denominational ar-
ranged counters; and a carrying member
for the counter of higher denomination; of
a detent controlled by the counter of lower
denomination to lock the carrying member
100 in potentially effective position, said detent
being adapted for displacement at varying
times during the cycle of operation of the
machine; a spring to return the detent to,
and retain it in, effective position; and
means to supplement the spring, to posi-
105 tively effect the return of the detent to ef-
fective position at a predetermined and
constant period in the cycle of operation of
the machine independently of the spring.

11. In a transferring mechanism, the combi-
110 nation with a pair of denominational
counters; of a carrying member shiftable to
effect a carry onto the counter of higher de-
nomination; a drive member for the counter
of lower denomination; a spring-restored
115 detent supported independently of the
carrying member for movement relatively
thereto, to lock the carrying member in
cocked position; means on the counter of
lower denomination, to trip the detent; and
means to reset the carrying member, the
120 carrying member equipped with means to
limit the travel of the detent relatively
thereto, and to positively insure and enforce
the complete restoration of the detent to
effective position.

12. In a transferring mechanism, the combi-
125 nation with a pair of denominational
counters; of a carrying member shiftable
to effect a carry onto the counter of higher
denomination; a drive member for the

counter of lower denomination; a spring-
restored detent supported independently of
the carrying member for movement rela-
tively thereto, to lock the carrying member
5 in cocked position; means on the counter of
lower denomination, to trip the detent; and
means to reset the carrying member, the
carrying member equipped with means to
restrict the displacement of the detent rela-

tively thereto, and of such contour as to 10
positively lead the detent directly to its
effective locking position as the carrying
member is reset, in case of failure of the
spring to restore the detent.
